RING

Andrew Zimet, New York, N. Y.

Application September 14, 1951, Serial No. 16,632

Term of patent 3½ years

(Cl. D45—10)

To all whom it may concern:

Be it known that I, Andrew Zimet, a citizen of the United States of America, residing in New York city, county of New York, and State of New York, have invented a new, original, and ornamental Design for a Ring, of which the following is a specification, reference being had to the accompanying drawing, forming part thereof, wherein:

Figure 1 is a front perspective view of a ring, showing my new design.

Figure 2 is a side elevational view, and

Figure 3 is a rear perspective view of the ring shown in Figures 1 and 2.

I claim:

The ornamental design for a ring, substantially as shown.

ANDREW ZIMET.
